SHIRRING ATTACHMENT FOR SEWING MACHINES

Edward L. Seaman, Garden City, N. Y., assignor
to S. & W. Sewing Machine Attachment Co.,
New York, N. Y., a partnership

Application October 9, 1952, Serial No. 313,933

5 Claims. (Cl. 112—134)

1

This invention relates to sewing machines and attachments therefor, and more particularly to apparatus for making shirring and scalloped shirring.

Heretofore in sewing machines provided with shirring mechanism, the practice has been to provide a plate over which the material to be shirred passes and above which a shirring blade is caused to reciprocate to shirr the material passing over the plate. The plate has usually been attached to or suspended above and parallel to the base of the machine just in advance of the presser foot and usually spaced from the base so that a layer of base material may move beneath the plate and have the shirred material sewed to it. In all such devices the plate on which the shirring is formed by the reciprocating blade constitutes an obstruction on or close to the base of the machine in advance of the sewing position which interferes with the free manipulation of the article being worked on. The principal object of this invention is to provide shirring mechanism which leaves the machine base entirely clear and unobstructed.

Another object is to provide improved means for producing scalloped shirring with such mechanism.

A further object is to provide the apparatus in such form that it may readily be applied to existing machines in the form of an attachment requiring no alteration in the basic machine structure.

In accordance with the invention, shirring is accomplished by means of structure in which the shirring blade operates in a direction which is the opposite of that heretofore employed; that is to say it is urged rearwardly and upwardly instead of downwardly and shirrs against the underside of an upwardly extending and preferably angularly disposed plate in advance of the needle. This plate may conveniently be attached to or made a part of the presser foot. Preferably it is part of a specially made presser foot which may readily be installed on the presser foot bar in the usual way. The shirring blade is resiliently urged against the forward face of this plate and reciprocated by any suitable mechanism. The machine base is thus left entirely clear of obstructions right up to the place where the material being sewn passes beneath the needle and into the feeding means of the machine.

The material to be shirred is fed by a guide, or, if desired, by a combined folder and guide, between the above described shirring plate and shirring blade and, to form scalloped shirring, this

2

guide is caused to reciprocate laterally of the line of stitching.

The invention will best be understood from the following detailed description of the present preferred embodiment thereof, taken in conjunction with the drawings, in which:

Fig. 1 is a front elevation of a sewing machine embodying the novel mechanism for making scalloped shirring;

Fig. 2 is a top plan view thereof with part of the machine head broken away;

Fig. 3 is a detailed end elevation on the line 3—3 of Fig. 2 with some parts omitted and the supporting arm cut away, showing the principal parts of the shirring mechanism;

Fig. 4 is a plan view of a form of trimming produced by the machine in which the scalloped shirring is shown as stitched to a base fabric; and

Fig. 5 is a perspective view of the combined presser foot and shirring plate forming part of the invention.

The side of the machine toward the operator will, in the ensuing description, be referred to as the front.

Referring to the drawings, they show a standard sewing machine having a base 10 with a head having an overhanging arm 11 and a needle head 12 which carries a reciprocating needle bar 14 in which a needle 15 is secured, all in the usual manner. The head also carries a presser foot bar 16 to which is secured the foot 18, of special construction as hereinafter described, beneath which (not shown) are the usual oscillating feed dogs which advance the material underneath the presser foot in a rearward direction. The machine is provided with the usual rotating main shaft 19 to which is secured the hand-wheel 20 and pulley 21 through which the machine is driven. Attached to the main shaft 19 is a sprocket 22, from which an auxiliary shaft 24 is driven by the cleated belt 25 through the sprocket 26. This drive belt is preferably surrounded by a guard 27 attached to a casting 27a which is fixed to the base 10 of the machine by an angle bracket 28, the casting 27a also serving as a bearing for one end of the shaft 24. Attached to the head 12 is a transversely and forwardly extending supporting bracket 29 having a portion 30 in which the shaft 24 is rotatably supported near its other end. Bracket 29 is secured to the inner vertical face of head 12 by threaded stud bolts 31, on which it is held between the positioning nuts 32 and lock nuts 34. Shaft 24, which rotates with main shaft 19, actuates the shirring

55

and guide reciprocating mechanisms which will now be described.

Referring particularly to Figs. 3 and 5, the shirring mechanism includes a shirring plate 35 and a shirring blade 36 which are arranged and cooperate in a novel manner. In the embodiment shown, the shirring plate is part of the specially constructed presser foot 18 which also has a flat portion 38 which overlies the feed dogs and contains a needle hole 39 and has an upwardly extending attaching portion 40 which fits the presser foot bar 16 to which it is secured by the bolt 41. Plate 35 is of such a width as to be wider than the material to be shirred and of a height greater than the maximum distance of travel of the shirring blade 36. As shown, it extends upwardly and preferably slopes forwardly away from the needle 15 although the angle at which it is disposed may be varied considerably.

Shirring blade 36 is attached to a hub 42 fixed on a shaft 44 which is rotatably mounted in an arm 45 which is adjustably secured by screw 47 in the slotted arm 46 mounted on the stub shaft 48 rotatably supported in the boss 49 at the forward end of bracket 29. The shirring blade 36 is urged upwardly and rearwardly toward the plate 35 by a coil spring 50 surrounding the shaft 44. Reciprocating motion is imparted to the shirring blade from shaft 24 through the eccentric 51, link 52 and the slotted arcuate arm 54 to which the link is adjustably connected by means of the bolt 55. The position of the link 52 with respect to the arm 54 determines the amount of travel of the blade 36.

The material to be shirred is fed between plate 35 and blade 36 by a guide or a combined folder and guide 58 having a bracket 59 attached to a slide block 60 which rides on a fixed square bar 61. One end of this bar is secured in a bearing bracket 62 and is further supported by angle bracket 63 attached to bracket 29. Bracket 62 has an integral boss 64 drilled to receive a supporting bar 65 which extends forwardly from the portion 30 of bracket 29 in which it is anchored. Bracket 62 also serves as a bearing for the transverse shaft 66 on the rear end of which is a pinion 68 driven by a worm 69 on shaft 24. On the front end of shaft 66 is a slotted disk 70 in the slot of which is an adjustable crank arm 71, the position of which is fixed by the set screw 72. Connecting one end of arm 71 and the slide block 60 is a connecting rod comprising the relatively adjustable arms 74 and 75 held together by the screws 76.

As the machine runs and shaft 24 rotates, the slide block 60 will be caused to traverse the square bar 61 by a distance determined by the position of arm 71 relative to disk 70, thus moving the material to be shirred back and forth laterally of the line of stitching. If arm 71 is so adjusted as to place the pivot point of arm 75 at the center of disk 70, the guide 58 will remain stationary.

Fig. 4 illustrates the type of trimming produced when the guide 58 is caused to reciprocate, the trimming 78 taking the form of scalloped shirring which may be attached to a base fabric 79. The line of stitching produced by the sewing machine is indicated at 80. If guide 58 is not reciprocated, straight shirring will be produced and it will be evident, therefore, that the mechanism is capable of adjustment to produce a variety of shirred materials.

It is to be understood that the invention is not limited to the details of construction of the embodiment above described for purposes of illustration and that many variations may be made

therein without departure from the invention as defined in the appended claims.

What is claimed is:

1. A scalloped shirring attachment for a sewing machine of the type having a base, a main shaft, an arm above said base, a needle head thereon, a needle bar having a needle and a presser foot bar having a presser foot carried by said head; said attachment comprising, an auxiliary shaft paralleling the main shaft and having a driving connection therewith, a transverse shaft driven from said auxiliary shaft, a shirring plate extending upwardly from said presser foot in advance of the needle, a pivotally supported shirring blade resiliently urged toward the forward face of said plate, means driven from said auxiliary shaft for reciprocating said blade, a fixed bar extending transversely of the line of stitching in advance of the needle, a slide block on said bar, a crank on said transverse shaft, a connecting rod joining the crank to said slide block, and a guide carried by said slide block arranged to direct material to be shirred downwardly between said shirring plate and blade, said attachment being supported wholly above said base.

2. An attachment according to claim 1 wherein said crank is adjustable relative to the axis of said transverse shaft to vary the travel of said slide block.

3. An attachment according to claim 1 wherein said slide block is non-rotatably and slidably supported on said fixed bar.

4. Reciprocating guide means for a scalloped shirring attachment for a sewing machine having a base and a main shaft comprising, an auxiliary shaft parallel with the main shaft, means driving the auxiliary shaft from the main shaft, a transverse shaft extending at a right angle to the auxiliary shaft, a driving connection between the auxiliary and transverse shafts, a crank on said transverse shaft, a fixed bar extending transversely of the line of stitching, a slide block non-rotatably supported thereon, and a shirring material guide carried by said slide block, said guide means all being supported above the machine base to leave the same free for the passing of goods being worked on.

5. Shirring mechanism for a sewing machine of the type having a horizontal base, feeding means including a presser foot to move the work across the base, and a vertically reciprocating needle operating adjacent said feeding means; said mechanism comprising an upwardly extending and forwardly sloping shirring plate supported from said presser foot in advance of said needle and above said base, a downwardly extending shirring blade pivotally supported in advance of and above said plate, means resiliently urging said blade upwardly and rearwardly toward the forward sloping face of said plate, means for reciprocating said blade relative to said sloping face in a downwardly direction toward said base, and a downwardly extending guide positioned to direct material to be shirred between said plate and said blade, said blade and said reciprocating means being positioned wholly above said base and at a substantial distance therefrom whereby said base is clear of obstructions up to said shirring plate.
